UNITED STATES PATENT OFFICE.

HUBERT C. BEYANT, OF HARTFORD, CONNECTICUT.

Brake for Talking-Machines.

1,300,568.

Specification of Letters Patent. Patented Apr. 15, 1919.

Application filed December 28, 1917. Serial No. 209,323.

To all whom it may concern:

Be it known that I, HUBERT C. BRYANT, a citizen of the United States, residing at Hartford, in the county of Hartford and State of Connecticut, have invented certain new and useful Improvements in Brakes for Talking-Machines, of which the following is a specification.

This invention has relation to stops for sound reproducing machines, and has for its primary object to provide a device of this character which will be simple in construction and operation, thereby insuring positiveness of action, and permitting the article to be manufactured in an inexpensive manner.

Another object of the invention is to provide a stop, designed for embodiment in sound reproducing machines of the disk record type, of any standard make.

A still further object of the invention is to provide a stop for disk-record sound reproducing machines, embodying a braking mechanism for engaging the turn-table, means applicable to the tone arm for engaging the braking mechanism to operate the same when the selection is completed, together with an altered record formed with a spiral groove to receive the needle at the termination of the selection whereby to insure positive and quick operation of the stop in a manner which will be presently seen.

In addition to the foregoing my invention comprehends improvements in the details of construction and arrangement of the correlative parts to be hereinafter more fully described and particularly set forth in the appended claims:

In the accompanying drawings in which similar and corresponding parts are designated by the same characters of reference throughout the several views in which they appear:

Figure 1, is a view in top plan, partly in section, with parts broken away to show details of a standard form of sound reproducing machine of the disk-record type embodying my automatic stop.

Fig. 2, is a view thereof in side elevation.

50 Fig. 3, is a view similar to Fig. 1 with the parts in operative position.

Fig. 4, is a detail view in plan disclosing the braking mechanism proper, and

55 Fig. 5, is a view in section taken on the line 5—5 of the immediate preceding figure.

With reference to the drawings 10 indi-

cates the motor box, 11 the turn-table having the record 12 superposed thereupon, and 13 the swinging tone arm.

My invention comprises a plate 14 which is secured to the top of the motor box beneath the turntable adjacent the periphery thereof, and located in a line which passes through the axis of rotation of the turn-table and the axis of rotation of the tone arm. A brake lever indicated generally at 15 is provided, and the same consists of a substantially square plate 16 having opposite corners formed with extensions 17 and 18. The extension 17 is perforated to receive a rivet, bolt, or the like 19 which passes through the plate 14 to pivotally mount the brake lever thereupon. The other arm 18 is bent upwardly at its terminal as indicated at 20. The remaining two corners of the square plate 16 are formed with sleeves 21 which converge axially toward the extension 17, and the adjacent edges of the plate are provided with ears 22 integrally formed therewith. The sleeves loosely receive the ends of a friction member 23 in the nature of a cylindrical section of leather or similar material, the ears 22 being subsequently bent upward to cover the ends of the sleeves and to bear against the terminals of said member 23 as clearly shown in Figs. 4 and 5 of the drawings. It will thus be seen that the intermediate portion of the friction member 23, which, when in place is bent to arcuate formation, is in a position to engage the periphery of the turntable, the extension 17 being formed with offsets 25 to dispose the friction member in a plane to engage the turn-table. When the brake lever is disposed along a line coincident with a line passing through the axis of rotation of the turn-table and tone-arm, the friction member 23 will be out of engagement with the turntable thereby permitting the same to rotate. An oscillatory movement of the braking lever however, in either direction will serve to engage the friction member against the turn-table.

Adjacent the point of connection of the tone arm with the tubular support therefor there is secured an arm 26, formed of a single strip of material bent at one end to form a loop 27 which is embraced about the depending portion of the tone arm, the extremity of the looped portion being 110 apertured to receive a binding screw 28 which also enters an aperture in the strip,

whereby a thumb nut applied to the bolt may serve to secure the loop in firm frictional engagement with the tone arm so as to rotate the arm 26 therewith. The outer 5 extremity of the arm 26 may be bent slightly as indicated at 29 to engage the upwardly projecting portion 20 of the brake lever.

To facilitate the operation of my automatic stop it is desirable that each record 10 be formed with a semi-circular or spiral groove 30 upon its upper face, which groove may be a continuation of the inner terminal of the groove of the record in which the sound waves are recorded so as to direct the 15 needle sharply toward the center of the record after the selection has been rendered.

In use, the parts are adjusted so that when the needle is brought to a point lying substantially in a plane passing through 20 the center of rotation of the turn-table and the center of rotation of the tone arm, the extension 20 of the brake lever will be engaged by the arm 26 so as to engage the friction member 23 of the braking lever 25 against the periphery of the turn-table.

It will thus be seen that after the selection has been rendered, the needle will enter the groove 30 and the tone arm will be rapidly moved toward the position shown 30 in Fig. 3 thereby bringing the arm 26 of the tone arm into contact with the brake lever, applying the friction member there- 35 of to the periphery of the turn-table so as to arrest motion thereof. It will be seen 35 that owing to the fact that the groove 30 extends for approximately one-half the circum-ference of the record, the turn-table will be stopped practically instantaneously.

While I have illustrated and described 40 my invention with some degree of particu-larity, I realize that in practice various alterations thereover may be made, and I therefore desire to reserve the right and privilege of changing the form of the de- 45 tails of construction, or otherwise altering the arrangement of the correlative parts without departing from the spirit of the invention or the scope of the appended claims.

50 Having thus described my invention what I claim as new and desire to secure by Letters Patent is:—

1. A brake for sound reproducing ma-chines, including a lever pivoted at a point 55 beneath the turntable of the machine, a pair of sleeves carried by the lever, and a friction element having its ends seated in

said sleeves and its center presented toward said edge.

2. A brake for sound reproducing ma-chines, including a lever pivoted at a point 60 beneath the turntable of the machine, a pair of sleeves carried by the lever with their axes converging toward each other to-ward the edge of the turntable, and a bowed 65 friction element having its ends seated in said sleeves and its center presented to-ward said edge.

3. An automatic stop for sound reproducing machines, including a plate, a brake 70 lever pivotally connected at one end there- 75 to, said lever having an intermediate square portion, sleeves at opposite corners of said square portion, and a cylindrical section of soft material having its terminals engaged in the sleeves, whereby the intermediate portion of said friction member may engage the periphery of the turn-table.

4. A brake for sound reproducing ma-chines, including a lever pivoted at a point 80 beneath the turntable of the machine and offset in its body to a point opposite the edge of the turntable, a pair of sleeves carried by the elevated portion of the lever, and a friction element having its ends seated in 85 said sleeves and its center presented to-ward said edge.

5. A brake for sound reproducing ma-chines, including a lever pivoted at a point 90 beneath the turntable of the machine and offset in its body to a point opposite the edge of the turntable, a pair of sleeves carried by the elevated portion of the lever and with their axes converging toward each other toward the edge of the turntable, and a bowed 95 friction element having its ends seated in said sleeves and its center presented toward said edge.

6. An automatic stop for sound reproducing machines comprising a brake lever hav-ing an intermediate square portion with sleeves at two opposite corners and exten-sions from the remaining corners, a pivotal support for one extension, and a friction 100 element composed of a cylinder of leather 105 having its terminals inserted in said sleeves and its center bowed toward the edge of the turntable of the machine.

In testimony whereof I affix my signature in presence of two witnesses.

HUBERT C. BRYANT.
